UNITED STATES PATENT OFFICE.

FREDERICK HEATH, OF TACOMA, WASHINGTON.

HOLLOW-WALL CONSTRUCTION.

1,215,149.

Specification of Letters Patent. Patented Feb. 6, 1917.

Application filed July 7, 1913. Serial No. 777,665.

To all whom it may concern:

Be it known that I, FREDERICK HEATH, a citizen of the United States, and a resident of Tacoma, in the county of Pierce and State of Washington, have invented an Improvement in Hollow-Wall Construction, of which the following is a specification.

I construct a fire-proof wall by means of a hollow block or tile having web members 10 and voids so spaced and arranged that the loads are carried directly upon a line or practically continuous vertical members, the blocks or tiles being laid on their sides or horizontally instead of vertically, as is the 15 custom, so that the webs are over webs and voids are over voids.

In carrying out my invention the chief feature is the manner of laying blocks having a series of voids arranged longitudinally, the blocks being laid in such relation to each other in adjoining courses that the webs of each block in one course are in direct vertical alinement with the webs in the next one, and the central void of each block is in 25 direct vertical alinement with the space between the blocks in the adjacent courses.

In the accompanying drawing,

Figure 1 is a sectional perspective of a 12" hollow wall, each course composed of 30 one half or single block or tile and one double block or tile arranged and bedded according to my invention.

Fig. 2 is a similar view of a 16" wall, certain courses being formed of two double 35 blocks and the intervening or alternating courses being formed of one double and two half blocks.

Fig. 3 is a horizontal section on the line 3—3 of Fig. 2.

Fig. 4 is a perspective view of the double block or tile employed in my wall construction.

In the several figures, the double hollow blocks or tiles are indicated by *a* and the 45 hollow half blocks by *b*. The double block *a* has three lengthwise voids 1, 1, 2 and two vertical lengthwise webs 3 which are arranged along the lengthwise middle of the block and separated by the narrow space or 50 void 2. The half blocks *b* have a single lengthwise void 4. Both blocks *a* and *b* are in brick form, that is, rectangular and oblong.

In practice, the blocks will be made in 55 sizes to conform to courses of brick and the

usual thickness of walls so that workmen will not be confused as they are with unusual shapes. The preferable size will be 8" wide, 16" long, and 7½" high which would take the place of twelve ordinary 60 bricks. By making the blocks several different heights, as 2½", 5", 7½", and 10½", all the various wall levels can be worked out without cutting tile.

In all cases, the blocks are laid sidewise or horizontal, as shown in Figs. 1 and 2. In Fig. 1, each course is formed of a double block *a* and a half block *b*, the two alternating in position in adjacent courses, so that the whole block *a* is on the outside of the 70 wall in one course or layer and on the inside in the next one. In Fig. 2, one course or horizontal layer is formed of two whole blocks *a* and the next one is formed of a whole block *a* and two half blocks *b*, the latter being on the outside and inside and the whole block intervening.

The several blocks are bedded in mortar but the vertical spaces between them are left free or open, thus forming a series of narrow dry-air chambers. The blocks being laid sidewise or flatwise, they are well bedded and the blocks directly between the webs are properly filled with mortar.

A wall of any desired thickness may be 85 laid with the blocks and the webs and outer walls will be alined in all cases, so as to form practically continuous vertical bearings or columns and so that the central void of each block is in vertical alinement with 90 the space between adjacent blocks in the next course above and below, as clearly shown in Figs. 1 and 2, which is a feature of prime importance in hollow wall construction, both from the workman's point of 95 view and the strength of the wall. The thickness of the webs will of course be increased for heavy wall loads.

Offsets for joints, beams, window sills, lintels, and changes in the thickness of walls 100 may be made as readily as with brick.

What I claim is:—

1. A building wall composed of hollow blocks laid horizontally in courses one above another, each course including blocks having three longitudinal voids and laid with relation to similar blocks in the next course as described, so that the central void in one block is always directly opposite the space or joint between the blocks in adjacent 110

courses and the webs in one course are in vertical alinement with webs in the next course, as described.

2. A building wall composed of horizontal courses each formed of blocks having a single void, and other blocks having three voids arranged parallel longitudinally, the blocks being laid adjacently and alternating

with each other, the central void of the three-void blocks being in direct vertical alinement with the space between blocks in adjacent courses, as described.

FREDERICK HEATH.
